UNITED STATES PATENT OFFICE.

NATHAN T. BRADFORD, OF TERRA BELLA, CALIFORNIA.

PUMP.

Application filed February 8, 1927. Serial No. 166,739.

This invention relates particularly to deep well centrifugal pumps.

It is one object of the invention to provide a simple and efficient means for centering the driving shaft in the pump bowls.

It is another object of the invention to provide a pump of the character indicated wherein the frictional resistance of the revolving shaft in the pump bowls is reduced to a minimum.

It is also an object of the invention to provide a simple and efficient means for lubricating the various moving parts of the pump in the pump bowls and adjacent thereto.

Finally it is an object of the invention to provide a structure of the character indicated that will be economical to manufacture, quickly and easily assembled and disassembled, and highly efficient in its practical application.

In the drawing:

Figure 1 is a vertical transverse section through a pump embodying my invention.

Figure 2 is a section on line 2—2 of Figure 1.

Figure 3 is a section on line 3—3 of Figure 1.

Referring now more particularly to the drawing, I show the stationary parts of the pump structure comprising the following elements. In the present disclosure I show two bowls as 1 and 2 threaded together at 3, the bowl 1 carrying a suction pipe or section 4, and the bowl 2 being screwed on to a discharge casing section as 5.

The bowl 1 is provided with a concentrically arranged bearing 6 and an annular recess to receive an impeller neck as at 7.

The suction pipe 4 supports a step bearing 8 by means of webs 9, the bearing being provided with a bearing surface 10 in alignment with the bearing surface 6 of the bowl 1, and extending a distance above the upper edge of the step bearing 8 as shown at 11. Threaded into the bottom of the step bearing 8 as at 12 is an axially arranged tube 13. This tube extends into the uppermost bowl and is fitted with a plug at its upper end as at 14. Tube 13 is spaced a distance from the surrounding bearings as indicated at 15.

The bowl 2 carries a bearing 16 in vertical alignment with the bearings 8 and 10 and has an annular recess 17 to receive a portion of an impeller neck. The upper end of the central portion 18 of the bowl is internally

threaded as at 19 to receive the lower end of a tubular member 20 having an upper end of smaller diameter as shown at 21. This tube is provided with a bearing 22, the same being a continuation of the bearing 16 and in alignment therewith. The upper end of the member 20 is connected to a tube section 23 by means of a coupling member 24, the column, of which section 23 is the lower end, encloses the rotating shaft and provides a conduit for lubricating oil.

The rotating parts of this portion of the pump comprise a tube 25 mounted to rotate in tube 23 and threaded on to a coupling member 26 having a conduit 27 passing lengthwise therethrough. On to the lower end of the coupling is threaded a tubular section 28, this section being so proportioned that it will rotate smoothly on the tube 13 and in the bearing 16, extending downwardly to a point below the bearing 16 and having threaded engagement with the upper impeller 29.

Another tubular section is shown at 30 revolvably mounted on tube 13 and in bearing 6 of bowl 1 having threaded engagement with impeller 29 at its upper end and with impeller 31 at its lower end as shown.

Still another tubular section is shown at 32 having threaded engagement with impeller 31 at its upper end, its lower end extending downwardly into the step bearing and rotating on the tube 13 and in bearing 10. The impellers 29 and 31 are provided with annular recesses as at 33 and 34 to receive the upper ends of the bearings 10 and 6 as shown. Drainage conduits are shown at 35 and 36, one extending from bearing 16 to the exterior of bowl 2, and the other draining from bearing 6 into the well.

When the pump is in operation, oil from a source not shown is fed down between the structure 25, 26, 28 and the enclosing members 23, 21, 22 and 16 where it eventually passes out through conduit 35 into the well. Lubricating oil is also fed down through the inside of tube 25, through conduit 27, tube 28 and between the central bearing tube 13 and the several sections 30, 32 and into the step bearing 8 where it passes upwardly around the bottom section 32 and finally drains off into the well at 36.

By means of this construction the whole rotating structure is maintained in its true axial alignment, and it is correctly lubricated with a suitable oil at both ends of the pump

bowl structure, the intermediate bearings being water lubricated, as to the exterior of the rotating shaft, but the inside of the rotating shaft is oil lubricated throughout almost the entire length of the pump bowl assembly.

It is to be understood, of course, that while I have herein shown and described but one specific embodiment of the invention, changes 10 in form, construction and method of assembly and operation may be made within the scope of the appended claims.

I claim:

1. A pump structure comprising a pump bowl having a shaft bearing formed therein, a step bearing suspended below the same, an impeller mounted in said bowl, a tubular shaft revolvably mounted in said bearings and carrying said impeller, a fixed bearing 20 element axially mounted in the bottom of said step bearing whereby to form an inner bearing for said shaft, means for introducing a lubricating fluid between the tubular shaft and bearing element, and a drain from 25 the interior of the step bearing to the exterior thereof at a point above the lower end of the revolvable shaft.
2. A pump structure comprising a plurality of bowls mounted in operative relation 30 to each other, a bearing concentrically formed in each bowl, and a step bearing suspended below the lowermost bowl, a bearing element mounted in said step bearing in spaced relation thereto and extending axial- 35 ly through said bowls, a tube mounted upon the uppermost bowl in concentric relation thereto, a tubular shaft revolvably mounted in said last mentioned tube and having a coupling mounted on its lower end provided 40 with a conduit extending therethrough and communicating with the tubular shaft, and tubular shaft sections suspended from said coupling and revolving therewith and revolvably engaging the exterior of said bearing 45 element and the bearings of said bowls, a

drain from the upper bowl bearing, and impellers mounted on said tubular shaft within said bowls.

3. A pump structure comprising a pump bowl having a shaft bearing formed therein, 50 an impeller mounted therein and a step bearing provided with a bearing surface in alignment with the bearing surface of the bowl supported thereby, a fixed bearing element mounted in the step bearing and extending 55 axially through the bowl, and a tubular shaft mounted in the impeller and engaging the bearing surface of the step bearing and the bearing element, and the bearing surface of the bowl. 60

4. A pump structure including a pump bowl, an impeller mounted therein, a step bearing provided with a bearing surface concentrically arranged relative to the axis of the bowl supported thereby, a fixed central bearing element mounted in the step bearing and a tubular shaft mounted on the impeller and revolvably mounted between the step bearing and central bearing element. 65

5. A pump structure comprising a plurality of bowls mounted in operative relation to each other, a bearing concentrically formed in each bowl, and a step bearing suspended below the lowermost bowl, a bearing element mounted in said step bearing in spaced relation thereto and extending axially through said bowls, means for introducing lubricating fluid into the bearing of the uppermost bowl and drainage means therefrom, tubular shaft sections revolvably mounted in the bearings of said bowls and revolvably engaging the exterior of said bearing element, one shaft section extending between the step bearing and the bearing element, impellers mounted on said shaft sections within said bowls, means for introducing a lubricating fluid between said shaft sections and the bearing element and step bearing, and a drain from the step bearing. 70 75 80 85

NATHAN T. BRADFORD.
